GAS FURNACE

Richard E. Fraser, Stockton, Calif., assignor to
 Fraser Furnace Company, Stockton, Calif., a
 corporation

Application April 23, 1932, Serial No. 607,123

1 Claim. (Cl. 126—116)

This invention relates to gas floor furnaces and is a continuation in part of my application for patent, Serial No. 349,611, filed March 25, 1929.

The principal object of this invention is to im-

- prove the construction of furnaces of this type so as to increase their heating output with no increase in size or fuel consumption, by constructing and arranging the gas passage and heat radiating members of the furnace in such a way
- 10 that a great volume of air will be evenly heated and a very large percentage of the heat units in the gas utilized, with a consequent high efficiency of the furnace.

A further object is to construct the furnace so that the compactness necessary in this particular type is maintained, coupled with great efficiency and simplicity and inexpensiveness of construction and manufacture.

The objects I accomplish by means of such structure and relative arrangement of parts as will fully appear by a perusal of the following specification and claim.

In the drawings similar characters of reference indicate corresponding parts in the several views:

Fig. 1 is a sectional end elevation of my improved furnace of the floor type, shown partly in section.

Fig. 2 is a top plan view of the furnace with the top grate mostly broken away.

Referring now more particularly to the characters of reference on the drawings, the numeral 1 denotes a grate to rest on the floor, from adjacent the periphery of and secured to which a rectangular casing 2 depends. Supported on and projecting upwardly from the bottom 3 of the casing is the main gas chamber 4, freely open on the bottom and there connected to an open bottomed frame or casing 5, depending below the casing 2. This lower casing supports the gas burner 6 of suitable character and of a shape symmetrical with that of the chamber. The chamber terminates short of the top grate and has a centrally disposed and removable peep-hole cap 7 thereon.

On one side near the top the chamber communicates with separate vertical circular drums by means of lateral and relatively restricted outlets 9; said drums having cylindrical passages 10 therethrough concentric therewith and open to the area enclosed by the main casing both at top and bottom. The outlets 11 from the drums are adjacent the bottom and on the sides opposite to the intakes 9, and lead to the exterior of the casing 2 and are there connected to a common manifold 12 from which a single flue 13 leads. The

drums terminate short of the bottom of the casing a considerable distance so as to permit air from below to freely pass upwardly through the passages 10.

Projecting outwardly from the chamber 4 at 60 spaced intervals about the same are hollow fins 14, open to the interior of the chamber and extending from top to bottom of the same. There are more of these fins on the side of the chamber opposite the drums than on the drum side, since 65 said drums while spaced from the chamber are too close to permit of the fins being used except between and beyond the drums, as clearly shown in Fig. 2.

A double-walled inner casing 15 is secured to 70 and depends from the grate inwardly of the casing 2 and extends in surrounding relation to the structure below to a termination some distance short of the bottom 3. The inner casing is arranged so that it clears the outsides of the drums slightly 75 and also clears the outer ends of the end fins and the opposite side fins of the casing a corresponding distance. Air intake openings 16 are cut through the outer wall surface at the bottom, and similar openings 17 are cut through the inner wall surface at the top.

Semicircular horizontal baffles 18 are mounted in the drums just above their outlets and on the same side; said baffles extending between and contacting with the drum walls and those of the 85 inner cylindrical passages 10.

In operation the flow of gases from the burner to the outlet flue 13 will be self-evident. The use of cylindrical drums provides a relatively great air-flow space about the drums and between the 90 same and the chamber which permits of an uninterrupted upward flow of air as is necessary for efficiency; and at the same time gives plenty of room for welding the outlet connections together while maintaining the drums and chamber in 95 very compact relationship. The fins projecting between the drums and in overlapping relation to the same at the corners of the chamber cause such upwardly flowing volumes of air to absorb a considerable amount of heat from the fins so 100 that the air is thoroughly heated while at the same time the furnace chamber is kept cool and overheating of the metal walls thereof is prevented.

The cylindrical drums also cause the gases entering the same to whirl about and come in full 105 contact with all the surface area of the drum walls, thus delivering all possible heat units to said walls which in turn is radiated to the surrounding air.

The arrangement of the outlet manifold and 110

flue at the bottom of the drums avoids the smothering of the flame which would be had if the drums depended below the outlet; while the outlet being above the level of the burner prevents the killing of the flame which would be obtained if the outlet was at or below such level. Also the bottom of the drums being above the bottom and naturally hottest portion of the main heating chamber, the upwardly reflected heat from said hottest portion of the chamber keeps the bottom of the drums hotter than would otherwise be the case and has a tendency to prevent condensation in the bottom area of the drums.

The double walled intermediate casing 15 with the air openings which permit the intake of cold air to the space between said walls at the bottom and the discharge of air into the main air discharging area of the furnace at the top of said casing, not only provides additional heat radiation and air heating capacity in the furnace, but keeps the cold air passage area outwardly of said casing in a cooler condition than would otherwise be the case. This is because the continuous flow of initially cold air between the double walls of the intermediate casing draws off considerable heat from the casing walls and prevents the outer wall of the same from materially heating up. The incoming down draft of air therefore is kept cool and the temperature difference between such air and that in the furnace area proper is relatively great. As a consequence the velocity of such incoming air is increased with a consequent increase in furnace efficiency over one in which the flow of air to be heated is sluggish due to a lack of sufficient temperature difference between the hot and cold air flow.

The drums 8 being on one side of the main heating chamber only, the necessary connection with the outlet flue may be kept very simple and compact without the use of a plurality of manifolds and flues or without a plurality of intercommunicating passages of different sizes, one or the other of which arrangements would be necessary if the drums were disposed on both sides of the chamber.

The baffles 18 prevent the gases from flowing straight down between the intakes and outlets of the drums and cause such gases before reaching the outlets, to sweep the walls of the drums adjacent the furnace chamber, thus imparting great heat thereto with a corresponding great and efficient heating of the cold air currents passing up between the furnace chamber and the drums. The gases are also caused to sweep the bottom walls of the drums, thus further aiding to prevent condensation.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claim.

Having thus described my invention what I claim as new and useful and desire to secure by Letters Patent is:

A gas furnace comprising an enclosed casing adapted to be suspended from a dwelling floor, an open bottomed casing mounted on and depending below the bottom of said floor casing, a gas burner assembly mounted in the open bottomed casing and below the bottom of the floor casing, a main gas chamber resting on the bottom of the floor casing in surrounding relation to and in open communication with the open bottomed casing and extending to a point adjacent the top of the floor casing, a vertical drum to one side of and adjacent the chamber, said drum having an air passage therethrough from top to bottom, the lower end of the drum being spaced above the bottom of the floor casing, a gas intake passage between the chamber and the drum adjacent the top thereof, and an outlet passage from one side of the drum at the lower end thereof and a horizontal baffle in the drum just above and on the same side as the outlet.
